UNITED STATES PATENT OFFICE.

PETER COPLAND, OF PORTSMOUTH, ENGLAND.

STEERING AND PROPELLING MECHANISM FOR BOATS.

1,386,237.

Specification of Letters Patent. Patented Aug. 2, 1921.

Application filed April 13, 1920. Serial No. 373,675.

To all whom it may concern:

Be it known that I, PETER COPLAND, a subject of the King of Great Britain, and residing at Portsmouth, England, have invented certain new and useful Improvements in Steering and Propelling Mechanism for Boats, of which the following is a specification.

This invention relates to combined steering and propelling mechanism, with a reversing action applicable to ships, boats and the like, and has for its object to provide such mechanism in a simple form which can be conveniently and easily applied to all kinds of boats, the mechanism being substituted for the usual rudder and being supported by the rudder irons.

According to the present invention the rudder carries the propelling mechanism and is mounted in such a manner at the stern of the boat that it can be operated without interfering with the propelling mechanism, while the propelling mechanism can be controlled by driving ahead or astern or the propeller can be thrown out of action. For this purpose the propeller shaft is driven by a vertically movable shaft through bevel gear, arranged for driving in opposite directions, the shaft being adapted to be locked in any of the required positions by a spring catch.

In the accompanying drawing Figure 1 shows a side view of an example of construction according to the present invention, and Fig. 2 shows a detail of a modified form of construction.

On the usual rudder irons 1 at the stern of the boat 2 is mounted a board or plate 3 which is prevented from turning on the rudder irons by means of plates or clamps 4 fitted with set screws 5 adapted to engage with the transom 6 of the boat and thus hold the plate 3 rigidly in position. If desired, however, the board or plate 3 could be secured permanently to the stern of the boat in any suitable manner.

To the board 3 are secured bearings 7 in which is mounted a vertical shaft 8 carrying at its lower end two bevel pinions 9, 10 arranged for driving in opposite directions. To the lower end of the rudder 14 is

secured, by plates 38 and 40 a casting 16, while the rudder is also formed with an aperture at 18 to accommodate the propeller 19. The driving shaft 8 passes through bearings in bosses 39 formed on the casting, and the rudder 14 with the casting 16 is thus free to turn on the driving shaft 8. In the casting 16 is also formed a bearing 17 in which is mounted the propeller shaft 13, and on this shaft 13 are keyed the propeller 19 and a bevel wheel 12. The bevel wheel 12 is adapted to be brought into gear with one or other of the bevel pinions 9, 10 for driving ahead or astern. The bevel pinions are preferably separated by a distance piece 11 which is of such a length that the driving shaft 8 may be moved into a position in which the bevel wheel 12 is mid-way between the two bevel pinions 9, 10 and does not gear with either of them.

The upper end of the shaft 8 is preferably of square section at 20 and slides through the boss of a sprocket wheel 21. If desired, however, the shaft could be round and provided with a key engaging in a corresponding slot in the boss of the sprocket wheel or other suitable means could be provided for the purpose of preventing any relative turning movement of the wheel and the shaft while at the same time permitting the shaft to move vertically.

The sprocket wheel 21 is mounted in a cage composed of two arms 22, 23 so as to prevent any lateral movement thereof. The arm 23 is provided near one end with a socket 24 fitting on the head of the board 3 while the free forward end of the said arm is secured, by bolting or otherwise, to a cross beam 25 secured to the motor casing 26. The arm 22 is bolted to the arm 23 by bolts as at 27.

The drive from the motor 26 is transmitted to the sprocket wheel 21 by a sprocket wheel 28 and a chain or belt 29. It will, of course, be understood that instead of a chain and sprocket wheels, pulleys and belts could be used for transmitting the drive.

For the purpose of vertically moving the shaft so that one or other of the bevel pinions 9, 10 may gear with the bevel wheel 12 or in order that the shaft 8 may run free,

a lever 30 is pivoted as at 31 to the board 3, the lever 30 being forked at 32 so as to engage between collars 33, mounted on the shaft 8, or with an annular groove on said shaft 8. On the lever 30 is slidably mounted a catch 34 which is drawn, by means of a spring 35, into engagement with notches 36 in a rack bar 37 secured to the arm 23. On the operation of the lever 30 the driving shaft 8 is moved into a position for propelling ahead or astern, or into the free position being locked in any one of these positions by the engagement of the spring catch 34 in the corresponding notch 36. In the construction shown, for example, the upper notch would correspond to the position for "ahead," the central notch to the disengaged position and the lower notch to the position for "astern."

20 The rudder 14 is provided with the usual tiller or yoke 37^a by means of which it can be operated to steer the boat without in any way interfering with the propelling mechanism, the rudder being free to turn on the driving shaft 8 as hereinbefore described.

The bevel gearing 9, 10 and 12 will preferably be incased for example in a light, water-tight casing 41, shown in section in the drawing, attached to the casting 16.

30 According to a modified form of construction as shown in Fig. 2, the bevel pinions 9, 10 are mounted so as to be free to slide on the shaft 8 and are in continual engagement with the bevel wheel 12 on the propeller shaft 13. This arrangement avoids the possibility of stripping the teeth on the bevel pinions when bringing them into gear by raising or lowering the shaft 8. In order to drive the bevel wheel 12 from the shaft 40 8 a clutch member 42 is secured to the shaft which is adapted to engage with one or other of the clutch faces 43, 44 provided on the bevel pinions 9 and 10 respectively so as to drive the wheel 12 for driving ahead 45 or astern. The clutch member 42 is so arranged that the shaft 8 may be entirely disconnected from the propeller shaft 13, when the clutch member 42 is in the mid position as shown.

50 The combined steering and propelling mechanism can be applied conveniently to any boat as it fits on the usual rudder irons in place of the rudder, and can be removed easily for inspection or repair. The motor 55 26 may be of any convenient type and is secured to the transom 6 of the boat 2 where it is within easy and convenient access.

Having thus described my invention what I claim as new and desire to secure by Letters Patent is:—

1. In a steering and propelling mechanism for boats, a vertically movable driving shaft, a forked lever pivotally mounted and engaging with said vertical shaft for the purpose of raising and lowering the same, means

for locking the forked lever in three different positions, a rudder rotatably mounted on said vertical shaft, a lever secured to said rudder, said lever being used for operating the rudder for steering while the forked lever remains stationary in its locked position, a propeller shaft with a propeller thereon mounted in the rudder, a bevel wheel on the propeller shaft, and two bevel wheels mounted on the vertical shaft on opposite sides of the bevel wheel on the propeller shaft.

2. In a steering and propelling mechanism for boats, a vertically movable driving shaft, a forked lever pivotally engaging with said vertical shaft for the purpose of raising and lowering the same, a rack and spring catch co-operating with the forked lever for holding it in three different positions, a rudder with an opening therein rotatably mounted on the vertical shaft, a lever secured to the upper end of said rudder, said lever being used for operating the rudder for steering while the forked lever remains stationary, a frame and a set of three bevel pinions carried therein in intermeshing relation, the vertically movable shaft passing freely through two of said bevel pinions, clutch faces on said two bevel pinions, a clutch member on the vertical shaft adapted to be engaged with either of said clutch faces, a propeller shaft operatively connected with the middle pinion of the set of bevel pinions and a propeller on said propeller shaft, the pivoted lever being adapted to hold the vertical shaft in three positions so that in one position one of the bevel pinions drives the pinion on the propeller shaft, in a second position the second pinion drives the pinion on the propeller shaft, and in the third position the propeller shaft is not driven.

3. A steering and propelling mechanism for boats comprising a board with means for securing the same to the transom of the boat, bearings on said board, a vertically movable driving shaft mounted in said bearings, a rudder with independent means for operating the same, the rudder being rotatably mounted on the vertical shaft and having an opening therein, a casing mounted on the rudder and inclosing the lower end of the vertical shaft, a propeller shaft with a propeller thereon mounted on the rudder and projecting into the casing, the propeller rotating in the opening in the rudder, two bevel wheels with clutch faces freely mounted in said casing and having the vertical shaft passing freely through said bevel pinions, a bevel pinion mounted on the propeller shaft, said pinions being in intermeshing relation, a clutch member secured to the vertically movable shaft and adapted to be engaged with either of said clutch faces, a forked lever engaging with the vertically movable shaft for the purpose of raising and lowering the same, means

pose of raising and lowering the same, and a rack and spring catch coöoperating with the lever for holding it in three different positions, whereby in one position of the vertical shaft the propeller shaft is not driven, in another position of the vertical shaft the propeller is driven through the clutch and one of the bevel pinions engaged therewith, and in a third position the propeller shaft is driven in the opposite direction through the clutch and the other bevel pinion with which it is then engaged. 10

PETER COPLAND.
